UNITED STATES PATENT OFFICE.

ASA W. WILKINSON, OF NEW YORK, N. Y.

IMPROVEMENT IN OXY-HYDROGEN GAS-BURNERS.

Specification forming part of Letters Patent No. 124,869, dated March 19, 1872.

To all whom it may concern:

Be it known that I, ASA W. WILKINSON, of the city, county, and State of New York, have invented a new and useful Improvement in Oxy-Hydrogen Gas-Burner; and I do hereby declare the following to be a full, clear, and exact description thereof, which will enable those skilled in the art to make and use the same, reference being had to the accompanying drawing forming part of this specification, in which drawing—

Figure 1 represents a vertical central section of this invention. Fig. 2 is a side view of the same. Fig. 3 is a plan or top view of the same.

Similar letters indicate corresponding parts.

This invention relates particularly to the tip of the burner, which consists of a tapering plug fitted nicely into the mouth of the hydrogen-discharge pipe and provided with a central opening to fit the end of the oxygen-discharge pipe, and with oblique jets round the central opening for the discharge of the hydrogen, while the face of the tip is concave in such a manner that by the relative position of the hydrogen-jets in relation to the central oxygen-jet, and particularly by the concavity of the face of the tip, the two gases are brought in intimate contact on discharging from the tip, and thereby a perfect and economical combustion of the hydrogen or other combustible gas is effected.

In the drawing, the letter A designates my tip, formed of a tapering plug of metal, lava, soap-stone, or other material suitable for the purpose. This tip is fitted nicely into the mouth of the hydrogen-discharge pipe B, which screws on a casting, C', perforated with two channels, a a', one of which forms the communication between the hydrogen-dis-

charge pipe B and the hydrogen-supply pipe H, while the other leads from the oxygen-supply pipe O to the oxygen-discharge pipe D. (See Fig. 1.) This last-named pipe extends up through the hydrogen-discharge pipe in an oblique direction, so that its top meets the center of the tip A, which is bored out to receive the same. Round the central hole in the tip are bored four, more or less, small holes or jets, b, which lead into the hydrogen-discharge pipe, and which are slightly converging from the inside out, so that the jets of gas discharging from the same will cross each other over the center of the tip. The face of the tip is provided with a hemispherical depression, c, which forms a mixing-chamber for the gases, and which materially assists to bring the oxygen in intimate contact with the combustible gas and to produce a complete and economical combustion.

My tip is not soldered to nor otherwise fastened to the burner, so that it can be readily removed and replaced by one of different form or shape, according to the nature of the gas to be burned or according to the flame to be produced.

What I claim as new, and desire to secure by Letters Patent, is—

The tip A, provided in its face with a depression, c, in combination with discharge-pipes B and D for hydrogen and oxygen, said tip being furnished with a central hole to fit the end of the oxygen-discharge pipe, and with oblique jets leading into the hydrogen-discharge pipe, substantially in the manner herein shown and described.

A. W. WILKINSON.
